UNITED STATES PATENT OFFICE.

LEWIS J. GREENE AND GOOLIE BURDETT, OF TIoga, PENNSYLVANIA.

TRAIN-ORDER HOLDING AND DELIVERING DEVICE.

No. 909,585.

Specification of Letters Patent.

Patented Jan. 12, 1909.

Application filed October 21, 1908. Serial No. 458,826.

To all whom it may concern:

Be it known that we, LEWIS J. GREENE and GOOLIE BURDETT, citizens of the United States, residing at Tioga, in the county of 5 Tioga and State of Pennsylvania, have invented a new and useful Train-Order Holding and Delivering Device, of which the following is a specification.

This invention relates to train order holding and delivering devices and has for its object to provide means for delivering orders to the engineer or conductor of a moving train without the necessity of stopping the train or without danger to the operator 10 or recipient of the order.

A further object is to provide a holder including a handle having a pair of spring clamping arms secured thereto and arranged to receive a hoop, the latter being provided 20 with means for supporting a train order or other message so that the engineer or other person on a train may readily detach the hoop from the holder by passing his arm through the hoop as the train travels past a 25 station.

A still further object of the invention is generally to improve this class of devices so as to increase their utility, durability and efficiency as well as to reduce the cost of 30 manufacture.

Further objects and advantages will appear in the following description, it being understood that various changes in form, proportions and minor details of construction 35 may be resorted to within the scope of the appended claims.

In the accompanying drawings forming a part of this specification:—Figure 1 is a perspective view of the holder with the 40 order carrying hoop in position thereon. Fig. 2 is a perspective view of the order carrying hoop detached.

Similar numerals of reference indicate corresponding parts in all of the figures of 45 the drawings.

The device forming the subject matter of the present invention includes an operating handle 5 to one end of which is secured a pair of spring clamping jaws 6.

50 The clamping jaws 6 are each preferably formed of a single piece of metal bent upon itself to produce a segmental groove 7, the fixed ends of the jaws being disposed substantially parallel with each other and riveted or otherwise rigidly secured to the ad-

jacent end of the handle, as indicated at 8. The grooves 7 of the clamping jaws are arranged in horizontal alinement with each other to form a pocket for the reception of the order carrying hoop or ring, indicated 60 at 9.

The hoop or ring 9 is preferably formed of a single piece of wire, the adjacent ends of which are overlapped and thence extended laterally to produce a loop 10 defining a plurality of pairs of spring clamping jaws 11 adapted to receive a train order or similar message 12.

The wire forming the opposite ends of the hoop is coiled or twisted around the main 70 body of the hoop, as indicated at 13, thereby to form a closure for the opposite ends of the loop 10 and also to retain the parallel portions of the wire constituting the jaws 11 in contact with each other so as to firmly 75 grip the train order when the latter is positioned between said jaws.

Attention is here called to the fact that the free ends of the clamping arms 6 are deflected laterally at 14 so as to assist in 80 guiding the ring or hoop 9 within the seating grooves 7, the arms 6 possessing sufficient resiliency to temporarily support the hoop or ring in the holder, but permit said hoop or ring to be readily withdrawn from 85 the clamping jaws when a slight pull is exerted on said hoop or ring.

In operation, a train order or other message is introduced within the loop 10 and then pressed laterally between either pair 90 of clamping jaws 11 after which the hoop is inserted in the groove 7 of the holder. The operator then grasps the handle 5 and supports the holder together with the hoop in the path of movement of a passing train 95 so that the engineer or conductor on said train may readily pass his arm through the hoop and detach the same from the holder, thereby to permit the removal of the train order. After the order is removed the hoop 100 or ring 9 may be thrown off at the next station or any other suitable disposition made of the same.

The holder and order carrying hoop are preferably made of galvanized iron so that 105 the same may be readily seen at night, but if desired, the same may be nickel, japanned or otherwise coated or protected.

From the foregoing description, it will be seen that there is provided an extremely 110

simple, inexpensive and efficient device admirably adapted for the attainment of the ends in view.

Having thus described the invention what is claimed is:—

1. A device of the class described including a hoop having its adjacent ends over-lapped and permanently secured to the body of the hoop to produce a closed loop adapted 10 to receive and clamp a train order.
2. A device of the class described including a hoop having its opposite ends over-lapped and permanently secured to the body of the hoop, the over-lapped ends of the 15 hoop being extended laterally to produce a closed loop defining co-acting jaws adapted to receive and clamp a train order.
3. A device of the class described including a holder, and a hoop detachably secured 20 to the holder and formed of a single piece of wire, the adjacent ends of which are over-lapped and coiled around the body of the hoop, that portion of the wire at the over-lapped ends thereof being extended laterally 25 to produce an intermediate loop defining clamping jaws adapted to receive a train order.
4. A device of the class described comprising a holder, and a hoop carried by the holder and formed of a single piece of wire 30 having its adjacent ends over-lapped and coiled around the body of the hoop, the over-lapped ends of the wire being extended laterally to produce a loop, and the wires on each side of said loop arranged parallel with 35 each other to form a plurality of spring clamping jaws adapted to engage a train order.
5. A device of the class described comprising a handle, spring clamping arms secured 40 to said handle and having registering grooves formed therein, and a train order supporting hoop seated in said grooves, the free ends of the clamping arms being deflected laterally to assist in guiding the hoop 45 within the grooves.

In testimony that we claim the foregoing as our own, we have hereto affixed our signatures in the presence of two witnesses.

LEWIS J. GREENE.
